CLAIM

The ornamental design for an ergonomic hand-held utility instrument and base system, as shown and described.

DESCRIPTION

FIG. 1 is a perspective view of a first embodiment of my invention;

FIG. 2 is an exploded perspective view thereof;

FIG. 3 is a right side elevation view thereof;

FIG. 4 is a left side elevation view thereof;

FIG. 5 is a front elevation view thereof;

FIG. 6 is a back elevation view thereof;

FIG. 7 is a top plan view thereof;

FIG. 8 is a perspective view of a second embodiment of my invention;

FIG. 9 is an exploded perspective view thereof;

FIG. 10 is a right side elevation view thereof;

FIG. 11 is a left side elevation view thereof;

FIG. 12 is a front elevation view thereof;

FIG. 13 is a back elevation view thereof; and,

FIG. 14 is a top plan view thereof.

The dot dot dash line showing portions of the ergonomic hand-held utility instrument with base system in FIGS. 1-14 form no part of the claimed design.
